UNITED STATES PATENT OFFICE.

BRUNO RÜTHLING, OF COLOGNE, GERMANY.

AIMING-STAND FOR RIFLES AND THE LIKE.

No. 800,492.

Specification of Letters Patent.

Patented Sept. 26, 1905.

Application filed October 21, 1904. Serial No. 229,466.

To all whom it may concern:

Be it known that I, BRUNO RÜTHLING, first lieutenant, a subject of the King of Prussia and German Emperor, residing at Hohenstaufenring 63, Cologne, Germany, have invented a certain new and useful Aiming-Stand for Rifles and the Like, of which the following is a full, clear, and exact description.

The present invention relates to an aiming-stand for shooting purposes; and the essential feature of the invention resides in the circumstance that a number of supports are so connected with a junction-piece that the latter serves as a rest for the rifle. Preferably the ends of the supporting-legs project different lengths from the junction-piece, so that, according to which ends of the legs rest on the ground, the junction-piece serves as a rest for the rifle at different elevations. The said supporting-legs are pivotally connected with said junction-piece so as by setting the legs at an inclination to regulate the elevation, the legs being maintained in such different positions by means of pins arranged on the junction-piece engaging said supporting-legs. Preferably on one of the legs or on one of the sides of the junction-piece is arranged a rail provided with notches serving to hold the rifle and which by being set inclined enables the elevation of the rifle-holder to be regulated. In this way also the various inclined positions are maintained by means of pins arranged on the junction-piece engaging said rail, and also for the purpose of securing such inclined position there may be used a folding leg arranged at one end of the rail. The supporting-legs connected to the junction-piece are preferably at their ends provided with extensions adapted to be turned on pivots, so that still further regulation of the elevation is possible.

In the accompanying drawings, which illustrate the invention, Figure 1 is a part elevation showing the connection of the junction-piece with the legs. Fig. 2 is a plan of the junction-piece with the legs. Fig. 3 is a perspective view of the parts shown in Figs. 1 and 2. Figs. 4 and 5 show details. Figs. 6 to 8 show modified forms of the junction-piece. Figs. 9 to 13 are perspective views showing various applications of the improved aiming-stand.

On the sides a^2 of the casing a there are arranged the supports b , pivoted around set-screws h . As shown in Figs. 1 to 3, the casing a is shown of triangular section, so that

three supporting-legs are employed. The top and bottom faces of the casing serve as rests for the rifle, and in order to properly support the rifle a pad may be placed on such faces. 60 The said faces may be either closed or opened. In Fig. 1 the lower face is shown closed by the base a' ; but the base-plate may be removed, as the pad can be sufficiently supported on the sides a^2 . The ends of the legs project different lengths in both directions from the pivots formed by the set-screws h , so that the aiming-stand may rest with the longer or shorter ends on the ground, either the top or bottom face of the casing a serving as a rest 65 for the rifle at different elevations—that is, the marksman may either stand or lie down, according to the position of the aiming-stand. Further variations of the elevation may be effected and controlled by setting the legs up 70 at different inclinations, and for maintaining such an inclined position there are interchangeably secured to the sides of the casing a pins d , against which the edges of the legs b are rested. Preferably the legs are provided 75 with plates i at the point engaged by the pins, and orifices p are formed in the casing at different positions, which are entered by the said pins d . The washers g on both sides of the legs b enable said legs, which are preferably 80 of wood, to turn more freely around the set-screws h . Pivotally connected with one of the legs b is a rail c , which preferably is mounted to rotate on one of the set-screws h . The upper edge of this rail c is provided with 85 notches, so that the said rail may serve as a rifle-rest. According to the inclination of the said rail, the elevation of the rifle-rest is regulated, and the rail may be secured at various positions by means of a pin d , interchangeably fixed in the casing. Preferably the end 90 of the rail c is provided with a supporting-leg s , pivoted at the point c' , and the legs b may be provided at their longer ends with 95 pivoted extensions b' . 100

Instead of the junction-piece being in the form of a casing, as shown in Figs. 1 to 3, the same may have the construction shown in Figs. 6 to 8. In this case three short tubes a^3 , connected together, have conical orifices 105 for receiving conical plugs x , through which pass the bolts y , which bolts serve to connect the legs b with the plugs x and, on the other hand, to secure the plugs x in the orifices of the members a^3 , Fig. 6. If instead of the flat legs b supporting-tubes u are employed, the said plugs x may be provided with eyes x' , 110

Figs. 7 and 8, in which the tubes *u* are secured. The connection of the tubes *u* with the junction-piece and the fastening of the same take place in the same manner as in the 5 arrangement shown in Fig. 6.

An aiming-stand such as described may be used for all possible methods of shooting. Fig. 9 shows the position with the marksman standing. Fig. 10 shows the position with the 10 marksman kneeling, the stand being moved from the one position to the other by shifting the pins *d*. Fig. 11 shows the position of the 15 stand with the marksman lying on the ground, the stand being inverted relative to Fig. 9 and the other face of the casing receiving the pad. By turning over the rail in the position shown in Fig. 11 the rifle can be rested in the same, as shown in Fig. 12. In this case the rail *c* is supported by the short leg *s*. If the 20 entire stand is again inverted to the position shown in Fig. 13, the rail *c* may be used as a rifle-holder for the marksman in standing position.

As above mentioned, the supports *b* are 25 formed at their ends with pivoted extensions *b'*, as shown in Figs. 4 and 5. Preferably the ends of the legs *b* are formed forked, as shown, so that the extensions rotate around the bolts *e'*, said extensions *b'* having points 30 *o*. Blade-springs *l* secure the said extensions in position. A screw-key *f* may be connected to one of the parts by means of a chain and serve for loosening the pins *d* and, on the other hand, for loosening the screws *h*. 35 The entire stand can be folded together, so as to be convenient for transporting.

What I claim, and desire to secure by Letters Patent, is—

1. An aiming-stand for rifles and the like, 40 comprising a plurality of legs, connected to and supporting a junction-piece, the said junction-piece serving as a rest for the rifle, the

ends of the legs extending different lengths in either direction from said junction-piece so as to adapt the stand for use at different elevations, substantially as described.

2. An aiming-stand for rifles and the like, comprising a junction-piece, a plurality of legs pivoted to said junction-piece and extending different lengths in either direction from the junction-piece, and pins interchangeably arranged on the junction-piece and supporting said legs, substantially as described.

3. An aiming-stand for rifles and the like, comprising a junction-piece, a plurality of legs connected to and supporting said junction-piece, said legs extending different lengths in either direction from the junction-piece, a notched rail pivotally arranged on one of said legs, and means for securing said rail in position on the leg, substantially as described.

4. An aiming-stand for rifles and the like, comprising a junction-piece, a plurality of legs connected to and supporting said junction-piece, a notched rail pivotally arranged on one of said legs, and a supporting-leg hinged to the end of said rail—substantially as described.

5. An aiming-stand for rifles and the like, comprising a junction-piece, a plurality of legs connected to and supporting said junction-piece, said legs extending different lengths in either direction from the junction-piece and extension-pieces pivoted to the ends of said legs, substantially as described.

The foregoing specification signed at Cologne, Germany, this 12th day of September, 1904.

BRUNO RÜTHLING.

In presence of—

WILLIAM KNEPPERS,
JOH. SCHULZ.
